UNITED STATES PATENT OFFICE.

RICHARD PARRISH, OF DETROIT, MICHIGAN.

ROPE-END DEVICE.

Application filed July 11, 1927. Serial No. 204,672.

This invention relates to rope end devices and is particularly adapted for use in connection with tow ropes such as are employed in connection with motor vehicles, the principal object being to provide an end for such ropes that is simple in construction, easily operated and effective in use.

Another object is to provide an end for a tow rope which may be securely fastened to an end of the rope portion thereof by a simple and quick operation and to which the tow rope may be simply, quickly and effectively secured to form a loop in the same.

A further object is to provide a rope end device which may be threadably clamped to an end of a rope and is provided with a helical end portion with which the rope may be quickly and effectively engaged to form a loop in the same.

20 The above being among the objects of the present invention the same consists in certain features of construction and combinations of parts to be hereinafter described with reference to the accompanying drawing, and 25 then claimed, having the above and other objects in view.

In the accompanying drawing which illustrates a suitable embodiment of the present invention and in which like numerals 30 refer to like parts in both views,—

Fig. 1 is a side view of my rope end device shown secured to the end of a tow rope and illustrating the manner in which such tow rope may engage the same to form a loop in the tow rope.

Fig. 2 is a view of Fig. 1 from the right hand edge of the sheet as viewed in the drawing.

I have found that one of the greatest objections to tow ropes, particularly of the type used in connection with motor vehicles, is the difficulty of securely fastening the end member thereof to the rope portion. Another difficulty I have found in connection 45 with such ropes is that in order to provide a loop in the same about a particular object such as an axle, bumper or the like, a difficult, tedious or unhandy operation must be gone through.

50 The principal object of providing the device herein shown and claimed is to provide an end for a rope that may be quickly and securely fastened to the same and with which the rope may be quickly and securely engaged to form a loop. As shown in the drawing the device comprising the present

invention comprises a sleeve member 10 having an end wall 11, it being open at the end opposite the wall 11 and having its walls adjacent the open end internally threaded. 60 An opening 12 is provided in the end wall 11 eccentric to the axis of the sleeve 10. Another opening 13 is provided in the side walls of the sleeve 10 slightly spaced from the bottom wall 11 and on the opposite side 65 of the sleeve 10 from the opening 12. Threadably received within the threaded end of the sleeve 10 is a member comprising the threaded portion 14 and tapered end 15. In practice a rope such as 16 is inserted 70 through the opening 12 into the interior of sleeve 10 and out through the opening 13 a short distance as indicated in Fig. 1. The member 14 is then threaded into the sleeve 10 until the tapered end 15 bears tightly 75 down against the rope 16 causing the same to be clamped between the bottom of the tapered end 15 and the end wall 11, and also jamming it tightly between the edge of the tapered end 15 and the lower edge of the 80 opening 13, thus securely and effectively clamping the rope 16 to the device.

The outer end of the member 14 is formed to provide a heavy helical coil 17 preferably having more than one convolution, each convolution being spaced from the adjacent convolution by a distance preferably slightly greater than the diameter of the rope 16.

85 In practice this device is employed in connection with a tow rope in the following manner: A tow rope is provided having a device as above described secured to each end thereof and one end of the tow rope is secured to the object to be towed and the other end is secured to the object in which is 90 to do the towing. The method of securing each end to its respective object is as follows: Considering, as a means of illustration, that the member 18 shown in the drawing is a part of the object to be towed 95 or which is to do the towing, one end of the tow rope is slipped over the same and brought back on itself under the member 18. The rope 16 above the member 18 is grasped in one hand and the end member is grasped in 100 the other. That part of the rope over the member 18 is then brought down into contact with the helix 17 immediately adjacent the threaded portion 14 as indicated by the dotted line "a" in the drawing and the rope 105 is then wound in a clockwise direction as viewed in Fig. 2 so as to bring it to the 110

successive positions shown by the dotted lines "b" and "c," respectively, in the drawing, and then pulled tight. This places the rope 16 above the member 18 within the center of 5 the helix 17, thus forming a loop in the end of the tow rope enclosing the member 18. The operation is then repeated at the other end of the tow rope and the rope is in position to tow the particular object necessary. In 10 order to release the tow rope from the member 18, the operation of placing the rope 16 within the center of the helix 17 is reversed, thus bringing the rope 16 out of the helix 17 after which the tow rope may be 15 pulled away from the member 18.

It will be apparent from the above description that not only is the device herein shown and described readily attachable to the end of the rope 16, but it also provides a 20 construction with which the rope 16 may cooperate in an easy, simple and effective manner to form a loop in the same about a particular member or object.

Although I have described this device for 25 use in connection with tow ropes for motor vehicles and the like, it is to be understood that I do not limit myself to this particular use of the same as the same may be employed not only in tow ropes or for other like purposes, but also for rope ends which may be 30 employed for any anchoring, fastening or other uses, and formal changes may be made in the specific embodiment of the invention described without departing from the spirit 35 or substance of the broad invention, the scope of which is commensurate with the appended claims.

What I claim is:

1. A device for securement to rope ends 40 comprising a member having side walls and an end wall, said end wall provided with an opening eccentric to said side walls, said side walls provided with an opening remote from the first mentioned opening, and a 45 plug threadably engaging said member provided with an end portion movable into adjacent relationship with both of said openings.

2. A device for securement to a rope comprising a cup shaped member provided with

an opening in the end wall thereof eccentric to the side walls thereof, said side walls being provided with a second opening spaced from said end wall and positioned on the opposite side of the said member from the 55 first mentioned opening, said openings providing a passage for a rope through the same, and a second member threadably engaging the inner walls of the first mentioned member and provided with a tapered end 60 movable into adjacent relationship with both of the said openings.

3. A device for securement to the end of a rope comprising a cup-shaped member provided with an opening in its closed end eccentric with respect to such end through which a rope is adapted to be passed, a second member threadably engaging the first mentioned member and adapted to clamp 70 said rope between itself and the first mentioned member, and an end on said second mentioned member comprising a helical convolution.

4. In combination, a cup shaped member provided with a pair of openings there-through, one of said openings being in the closed end of said cup and eccentric to the axis thereof, a rope extending through said openings, and a second member received within said cup shaped member and axially adjustable in respect thereto whereby to clamp said rope between the same and said cup shaped member, the second member being provided with a helix at one end thereof, the convolutions of which are separated by 80 a distance substantially not less than the diameter of said rope.

5. In combination, an interiorly threaded cup-shaped member provided with an eccentric opening in its closed end and a second opening in a side wall thereof diametrically opposite the first mentioned opening and spaced from said closed end, said openings providing a passage for a rope, a rigid helix, and a threaded end on said helix receivable 95 in said member, said end co-operating with said member to provide three projections adapted to clampingly engage a rope passing through said openings.

RICHARD PARRISH.
